CLOTHESLINE CANOPY

Otis B. Tout, San Diego, Calif.

Application April 11, 1934, Serial No. 720,047

1 Claim. (Cl. 135—5)

My invention relates to a canopy for a clothes line, and the objects of my invention are:

First, to provide a canopy wherein the canopy may be readily and quickly positioned or removed;

Second, to provide an apparatus of this class in which the clothes line and canopy may be tilted in either direction about a longitudinal axis whereby the several clothes line units may be lowered within ready reach;

Third, to provide an apparatus of this class wherein the readily tiltable nature thereof enables the canopy therefor to be positioned in such a manner as to protect the clothes from the sun, thereby providing an apparatus which is particularly suited for drying clothes subject to fading when exposed to the sun;

Fourth, to provide an apparatus of this class in which the canopy may be retained permanently thereupon inasmuch as the clothes may be fastened to the line without disturbing the canopy;

Fifth, to provide an apparatus of this class which is so arranged that the canopy may be fastened thereto and drawn into position with a minimum of effort and without lifting or attempting to throw the canopy over the clothes line frame, thereby providing an apparatus which is particularly suitable for use by women and children, and

Sixth, to provide on the whole a novelly constructed combined clothes line and canopy which is durable, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a perspective view of my combined clothes line and canopy with the canopy shown fragmentarily; Fig. 2 is an enlarged fragmentary sectional view through 2—2 of Fig. 1 showing the relationship of one of the cross arms and adjacent post; Fig. 3 is a transverse sectional view through 3—3 of Fig. 1 with the post shown fragmentarily and illustrating by solid lines the normal position of the clothes line and canopy and by dotted lines an inclined position assumed when placing clothes upon the clothes line; and Fig. 4 is a fragmentary sectional view taken along the same line as 3—3

but showing the cross arm in a position assumed when attaching the canvas or canopy prior to positioning the same and illustrating by dotted lines an intermediate position of the cross arm during such operation.

5

Similar characters of reference refer to similar parts and portions throughout the several views of the drawings.

Posts 1, journal bar 2, cross arms 3, bolts 4, spacers 5, brace member 6, pins 7, clothes line 10 units 8, canopy supporting lines 9, canopy 10, anchor hooks 11 and fasteners 12, constitute the principal parts and portions of my novel combined clothes line and canopy.

A pair of posts or uprights 1 are provided. 15 These journal a journal bar 2 which extends horizontally between the posts. The journal bar 2 is provided with a cross arm 3 adjacent each post. Each cross arm is secured to the journal bar by means of a bolt or other suitable pin 4 extending 20 therethrough so that the cross arms move in unison as the journal bar 2 is rotated. Spacers 5 may be positioned between the cross arms 3 and their respective posts 1.

At one end a cross arm 3 pivotally receives one 25 end of a brace member 6. Said brace member is provided with a plurality of perforations along its extended portion which are adapted to coact with a pin or several pins 7 provided in the corresponding post 1. The brace member 6 is so 30 arranged that it holds the cross arms in a horizontal position or in an inclined position such as shown in Fig. 3, it being noted that the cross arms may be inclined in either direction.

The normally under sides of the cross arms 3 35 are connected by a plurality of parallel disposed clothes line units 8 preferably formed of wire. The outwardly disposed clothes line units may be suspended a short distance below the cross arm on suitable supports 8a in order to provide sufficient clearance between the clothes line and the upper edges of the cross arms over which the canopy is positioned, as will be brought out hereinafter.

The upper edges of the cross arms 3 are connected by a plurality of canopy supporting lines 9 over which is positioned a canopy 10. By rotating the cross arms 3 until they occupy a position such as that shown by solid lines in Fig. 4, one edge of the canopy 10 may be attached thereto and for this purpose these ends of the cross arms are provided with anchor hooks 11. Upon attaching the canopy 10 to the anchor hooks 11 the cross arms are rotated in the direction of the arrows in Fig. 4 with the assistance of the brace 50 55

member 6 until the cross arms occupy the position shown by solid lines in Fig. 3 in which the canopy lies over the top of the canopy supporting lines 9. The remaining edge of the canopy 5 may then be secured by suitable fasteners 12.

In placing clothes upon the line first one side and then the other side is tilted downwardly, as shown in Fig. 3 so that the clothes line units are 10 readily accessible, the brace member 6 being used to retain the clothes line in the desired position. By tilting the clothes line and canopy said canopy 15 may be positioned so as to most effectively shield the clothes from the sun.

Though I have shown and described a particular construction, combination and arrangement of parts and portions, I do not wish to be limited to this particular construction, combination and

arrangement, but desire to include in the scope of my invention the construction, combination and arrangement substantially as set forth in the appended claims.

Having thus described my invention, what I claim as new and desire to secure by Letters Patent is:

In a canopy, a pair of posts, a bar journaled therein, cross arms secured thereto and carried thereby in unison, a plurality of canopy supporting lines connecting said cross arms, said cross arms and lines being rotatable a complete revolution in unison, a canopy, and means for attaching a margin of the canopy to corresponding ends of the cross arms whereby upon subsequent rotation of the cross arms the canopy is drawn over the supporting lines.

OTIS B. TOUT.
